(57) CLAIM

An ornamental design for a hockey short, as shown and described.

DESCRIPTION

FIG. 1 is a front perspective view of the hockey short;

FIG. 2 is a front view of the hockey short;

FIG. 3 is a rear view of the hockey short;

FIG. 4 is a top view of the hockey short;

FIG. 5 is a bottom view of the hockey short;

FIG. 6 is a right side view of the hockey short; and,

FIG. 7 is a left side view of the hockey short.

Certain features of the hockey short are shown in broken line format in the drawings and form no part of the currently claimed invention. Examples include a bib extending upwardly from the short, a pocket member, and straps disposed adjacent the pocket member.
